(57) **CLAIM**

The ornamental design for a toilet paper storage cabinet and dispenser, as shown and described.

DESCRIPTION

FIG. 1 is a top, front, and right side perspective of a toilet paper storage cabinet and dispenser showing my new design;

FIG. 2 is a front elevational view thereof;

FIG. 3 is a rear elevational view thereof;

FIG. 4 is a right side elevational view thereof, the left side elevational view being identical thereto;

FIG. 5 is a top plan view thereof, the bottom plan view being identical thereto; and,

FIG. 6 is a top, front, and right side perspective view of the toilet paper storage cabinet and dispenser shown with a top lid in an open position, and the broken-line disclosure understood to represent portions of the article in which the claimed design is embodied, but which forms no part of the claimed design.
